UNITED STATES PATENT OFFICE.

SAMUEL S. STEVENS, OF NORTH HOOSICK, NEW YORK.

CENTRIFUGAL PULP-DRIER.

SPECIFICATION forming part of Letters Patent No. 439,700, dated November 4, 1890.

Application filed July 26, 1889. Serial No. 318,774. (No model.)

To all whom it may concern:

Be it known that I, SAMUEL S. STEVENS, a resident of North Hoosick, in the county of Rensselaer and State of New York, have invented certain new and useful Improvements in Centrifugal Pulp-Driers; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

15 Similar letters refer to similar parts in the several figures therein.

My invention relates to improvements in centrifugal pulp-driers; and it consists of the novel construction and combination of 20 parts hereinafter described, and subsequently claimed.

Figure 1 of the drawings is a top plan view of my improved machine. Fig. 2 is an end elevation of same. Fig. 3 is a horizontal longitudinal section taken on the broken line 3 3 in Fig. 2. Fig. 4 is a top plan view of the friction-rolls and their bearings attached.

The object of my invention is to cheaply and rapidly extract water from pulp, and by 30 reducing its weight to lessen the expense of shipping it.

I convey a stream of wet pulp in liquid form into a rapidly-revolving perforated shell or hollow cylinder open at its ends, and preferably having its inlet-opening contracted; and I provide a stripping device interiorly of the shell adapted to strip the pulp from its interior surface as it is deposited thereon by the centrifugal force generated by the revolving shell.

40 A is the perforated shell having numerous perforations A' for the exit of the extracted water. The shell has the general form of a frustum of a cone and is provided exteriorly at or near its ends with bearing-flanges A² and A³, adapted to enter corresponding grooves B in the friction-rolls B'. The axles B² of the rolls have their bearings in the side plates of the troughs B³—one at 45 each end of the shell directly beneath the bearing-flanges. The troughs are secured to

the floor B⁴ or other support by the bolts or screws B⁵. At each end of the troughs an arch or yoke B⁶ is erected. These arches serve to support a water-screen B⁷, secured thereto, as by screws B⁸, at each end. They also serve to support a shaft C, rotating in bearings C', secured to the arches by screws C². The shaft is provided with a driving-pulley C³ fixed thereon and with the pulley C⁴ fixed thereon, and connected by belt C⁵ with a pulley C⁶, the spokes and hub of pulley C⁴ being broken away to better show the other parts. The pulley C⁶ is fixed upon the end of the stripper-shaft C⁷, which has its 60 bearings in the oscillatory links C⁸, pendent from the shaft C—one at each end of the shell.

The stripper-shaft C⁷ may be provided with any known form of stripping devices. I have shown projecting teeth C¹⁰ at one end and a 70 serrated blade C⁹ at the other end, extending spirally around the shaft. The stripper-teeth project farther from their supporting-shaft at its end located within the expanded opening of the shell, than they do at its other end, 75 so that the ends of all the teeth approach to about the same distance from the interior surface of the shell when the stripper-shaft C⁷ rotates about an axial line parallel with the axial line of the shell.

When desired, the stripper-shaft may have 80 all its teeth of equal length and have its axial line parallel with one of the sides of the shell, as indicated by the broken lines a b in Fig. 3. As shown in Fig. 2, the stripper is located 85 near the interior surface of the shell at one side of its axial center, and is provided with means for communicating to the stripper and its supports an oscillatory movement between such interior surface of the shell and axial center consisting of the eccentric D, fixed 90 upon shaft D' and having its strap D² connected by rod D³ with the link C⁸.

The shaft D' is supported by suitable bearings D⁴, secured to the arches as shown, and 95 can be rotated at any desired speed by suitable power (not shown) applied through pulley D⁵.

Revolute movement may be communicated to the shell itself in a well-known manner by 100 means of the belt F, passed over the shell upon the convexed pulley-surface F' and

down through the floor to a driving-pulley beneath, (not shown;) but I prefer ordinarily to impart rotary motion to the shell by means of supporting-rollers, as hereinafter described. 5 This belt not only serves to communicate revolute movement to the shell, but to hold the same down in place upon its supporting friction-rolls.

The wet pulp is introduced in a liquid form 10 into the contracted inlet of the shell through the supply-pipe F^2 , leading from a source of supply. (Not shown.) Just inside the inlet the shell is provided with the interiorly-projecting flange A^5 , adapted to prevent the liquid 15 pulp from spilling from the inlet.

The operation of the device is as follows: Revolute movement of the shell is maintained and the pulp admitted through supply-pipe F^2 and the inlet-opening, whereupon it 20 is forcibly pressed against the perforated shell by centrifugal force until the water is extracted, being driven by centrifugal force through the perforations in the shell and escaping beneath the floor. The stripper serves 25 to loosen the pulp from the surface of the shell and assist it on its passage through the shell and out of the expanding opening, to which it is continually impelled by the pressure upon the inclined sides of the shell. The 30 pulp in its passage through the shell parts with the water, which passes through the perforations in the shell, and emerges from the expanded end in a continuous flow of dry pulp.

35 When desired, the axles of the friction-rollers may be extended, as shown by dotted lines in Fig. 4, and provided with pulleys $J J'$ fixed thereon, the pulleys $J J$ being connected with each other by a belt J^2 , and the pulley J' connected with suitable power for the purpose 40 of imparting to the shell the required revolute movement, in which case the belt F may be dispensed with.

In describing my improved device I have 45 only referred to its use in extracting water from pulp; but I do not wish to be limited in its application to any particular use. It may be employed to extract any substance in a fluid form from a solid substance. The shell 50 is supported in a horizontal position, one side resting upon the friction rollers. I am thus able to communicate revolute movements to the shell about a horizontal axis, and leave the interior of the shell open and 55 unobstructed to receive the oscillatory stripper-shaft. The stripper-shaft bearings can be movably supported in any known manner, as well as by the oscillatory links C^8 , and can

be adjusted by the hand or in any known manner, as well as by the eccentric D . 60

I am aware that rotary cylinders have been provided with means for charging material into one end, and with blades for conveying it along the bottom of said cylinders to be discharged at the opposite end, and such construction is not of my invention; but my claim is limited to other features, which are hereinafter pointed out. 65

What I claim as new, and desire to secure by Letters Patent, is— 70

1. In a centrifugal pulp-drier, the combination, with a frusto-conical open-ended perforated shell revoluble about a horizontal axis and provided with a roller-engaging peripheral flange, of shell-supporting friction-rollers and means for communicating revolute movements to the shell, a wet-pulp-supply pipe leading into the smaller end of the shell, a stripper rotary in movable bearings, by which it is adjustably supported within 80 the shell, means for communicating rotary movements to the stripper, and means for communicating lateral movements to the stripper-shaft bearings, substantially as described. 85

2. In a centrifugal pulp-drier, the combination, with an open-ended perforated shell revoluble about a horizontal axis, of shell-supporting friction-rollers, means for communicating revolute movements to such shell, a wet-pulp-supply pipe leading into one end of the shell, a stripper located within the shell and rotary in pendent oscillatory bearings, means for rotating the stripper, and means for communicating oscillatory movements to the stripper-bearings, substantially 90 as described. 95

3. In a centrifugal pulp-drier, the combination, with an open-ended perforated frusto-conical shell revoluble about a central horizontal axis, of shell-supporting friction-rollers, means for communicating revolute movement to the shell, a wet-pulp-supply pipe leading into the smaller end of the shell, a stripper located within the shell and rotary upon 105 an axis parallel with a tapered side of the shell, and means for communicating rotary movements to such stripper, substantially as described. 100

In testimony whereof I have hereunto set 110 my hand this 20th day of July, 1889.

SAMUEL S. STEVENS.
